UNITED STATES PATENT OFFICE.

SIMON DE JAGER, OF PATERSON, NEW JERSEY.

ELECTRICAL SIGNALING.

SPECIFICATION forming part of Letters Patent No. 626,494, dated June 6, 1899.

Application filed May 26, 1898. Serial No. 681,758. (No model.)

To all whom it may concern:

Be it known that I, SIMON DE JAGER, a citizen of the United States, residing in Paterson, county of Passaic, and State of New Jersey, have invented certain new and useful Improvements in Electrical Signaling; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 My present invention relates to improvements in systems of transmitting electric signals; and its object is to provide a system in which the electric signals at a receiving-station respond to the pressing of the respective 20 keys at the transmitting-station, which latter is connected with the receiving-station by two metallic wires or by one metallic wire and one earth connection at each station.

The invention consists in the improved system of transmitting electric signals, substantially as will be hereinafter more fully described, and finally embodied in the clauses of the claim.

Referring to the accompanying drawings, 30 in which like letters and numerals of reference indicate corresponding parts in each of the several views, Figure 1 is a diagrammatic view illustrating the direction and divisions of the currents at the receiving-station connected 35 with the necessary means and contacts to compel the required signal to respond; Fig. 2, a vertical transverse section of a key arranged at the transmitting-station and also showing in a diagrammatic view its electric or wire connections; Fig. 3, an enlarged detail view of the top portion of Fig. 2, certain parts being shown in section, while others are broken away; Fig. 4, a sectional view on the line xx of Fig. 2; Fig. 5, a diagrammatic view of the electromagnet of one of the signals at the receiving-station and of the contact-breaker connected therewith; Fig. 6, a diagrammatic view illustrating the grouping and connecting of an increased number of signals at the receiving-station; Fig. 7, a diagrammatic view showing the connections between certain magnets and the shift-keys, and Fig. 8 is a diagram-

matic view showing the connections between the mechanisms illustrated in Fig. 1 with the signals and their immediate wiring removed 55 and in full the mechanism partially shown in Fig. 7, as hereinafter more fully described.

In said drawings, An Bn Cn and Ap Bp Cp represent different groups of magnets at the receiving-station, each group consisting of a 60 series of stationary magnets e' e^2 e^3 e^4 and of a movable magnet m' m^2 . These groups of magnets work in the same manner as described in my United States Letters Patent No. 590,398, and it must be remarked that 65 the movable or stationary magnets might all be electromagnets or that either the movable or the stationary magnets might be permanent ones.

For the purpose of simplifying the reading 70 of the drawings the stationary magnets e' e^2 e^3 e^4 have been illustrated in Fig. 1 as permanent magnets, while the movable magnets m' m^2 are illustrated as electromagnets.

If a current is sent through the movable 75 electromagnet in Fig. 1, this magnet will turn to the right or left, according to the direction of the current, making either m' positive and m^2 negative, or vice versa. It must be remarked that said electromagnet is supported 80 on an arm X , which is fulcrumed in its center, as at k , and is controlled by a spiral spring k^0 , adapted to return said arm (and magnet) to its normal or rest position when the current is broken. 85

In the patent above referred to I have described the manner in which by predetermined number of impulses of one polarity sent from the transmitting-station a corresponding number of movable magnets at the 90 receiving-station turn to one side and are kept in that position until the following impulse of the opposite polarity from the transmitting-station turns the next magnet in the opposite direction, causing the required signal to respond. Accordingly, if there are a great number of signals at the receiving-station and a corresponding number of keys at the transmitting-station the number of groups of magnets at the receiving-station must be 95 great and the number of impulses sent from the transmitting-station has to correspond. If, for instance, there are thirty-six keys at the transmitting-station, thirty-six impulses 100

must be sent away by pressing down the thirty-sixth key.

By my present invention the number of impulses required, and accordingly the number 5 of groups of magnets at the receiving-station, have been considerably reduced, whereby the great advantage is obtained that by pressing the key the duration of each separate impulse becomes much longer, as hereinafter stated. 10 The arrangement of the groups of magnets at the receiving-station and the manner in which contacts are made is precisely the same as that in United States Letters Patent No. 590,398.

15 In Fig. 1, S' S^2 to S^9 represent nine signals placed in three groups of three each, while Y is a source of electricity at the receiving-station, and c^7 and c^8 contacts attached to the connecting-arms of the movable magnets m' m^2 20 in the groups A_n B_n C_n and A_p B_p and C_p , respectively. One pole of the source of electricity Y is connected through the wire l with the binding-post l^X , and in turn connected through the wires 2, 3, and 4 with one side 25 of each of the contacts c^7 , while the other pole of the source of electricity Y is connected through a wire 5 with the binding-post S^X , in turn connected through wires 6, 7, and 8 with one side of each of the contacts c^8 . The other 30 sides of the contacts c^7 c^7 c^7 in the groups A_n , B_n , and C_n are connected by wires 9, 10, and 11 with the horizontal groups of signals S' S^2 S^3 , S^4 S^5 S^6 , S^7 S^8 S^9 , respectively, while the other side of the contacts c^8 c^8 c^8 in the groups 35 A_p , B_p , and C_p are connected by wires 12 13 14 with the vertical groups S^7 S^4 S' , S^8 S^5 S^2 , S^9 S^6 S^3 , respectively.

From the above it can be seen that the horizontal groups of signals are controlled by the 40 contacts c^7 , while the vertical groups of signals are controlled by the contacts c^8 ; but at the same time it must be remarked that the signals will only respond when a contact c^7 and a contact c^8 are closed at one and the 45 same time. It will also be seen that the two groups of signals are respectively arranged in two sets of branch circuits which have a common source of electrical energy at Y .

By the simultaneous closing of a contact c^7 50 and a contact c^8 the signal at the crossing-point of the respective horizontal and vertical groups will receive the strongest impulse from the source of electricity Y , and if said source of electricity is strong enough to send a current 55 through more than one electromagnet of the signals then one or more of the remaining signals will also respond. Should, however, said current be only strong enough to operate the electromagnet of one of the signals, then, of course, as above stated, the signal at the crossing-point of the horizontal and vertical groups will alone respond. For instance, if the contact c^7 in group A_n and the contact c^8 in group B_p are closed simultaneously 60 signal S^2 will respond. At this point I may remark that the response of the required

signal can easily be made independent of the strength of the source of electricity.

In Fig. 6, s' to s^{25} represent the electromagnets of twenty-five signals at the receiving- 70 station, and 80 to 84 the wires connecting an equal number of contacts c^7 (the same as in Fig. 1) with these magnets, while 90 to 94 represent the connection between the latter and an equal number of contacts, (like the 75 contacts c^8 c^8 in Fig. 1.)

It is apparent that if, for instance, the contact of wire 80 and the contact of wire 92 are being closed the signal s^8 will respond, but the current will at the same time pass through 80 a number of other electromagnets. In following the current closely it will be seen that s^8 is the only signal through which said current will go direct, while to reach one of the other signals it has not alone to pass through more 85 than one at the time, but also it must pass through one of them in opposite direction before the current can reach the other contact.

In Fig. 5 of the drawings is represented by f' f^2 the electromagnet for the signal S' of 90 Fig. 1. The wires 9 and 12 are the same wires as in said Fig. 1; but the said wire 12 does not connect the electromagnet directly with contact c^8 . It is connected with an intermediate-arranged contact-breaker L^X . This 95 contact-breaker is attached to a small magnet m , pivoted at x^m . One pole of this magnet—say the positive one—is placed between the poles of the electromagnet f' f^2 , while the other pole carries the contact-breaker. 100

If, for instance, the current from wire 9 to 12 goes in such a direction that f' becomes positive and f^2 negative, the magnet m cannot move; but if the said current goes in the opposite direction the magnet m will move in 105 the direction of the arrow, whereby the contact at L^X is broken.

If such an arrangement as just described for signal S' is attached to each signal, then only one signal will respond at the closing of 110 one of each of the two contacts c^7 and c^8 . The electromagnet of any of the other signals will only be reached by the current after it has passed through an electromagnet in opposite direction, causing then an interrupted current, which by proper arrangement of the contact-breaker will never be strong enough to let any other signal respond, notwithstanding 115 the strength of the source of electricity Y .

Reference-letters P and Q in Fig. 1 represent the binding-post at the receiving-station with which the wires from the transmitting-station are connected, while reference-letter E represents an ordinary electromagnet, and L a lever which can move on its axis and which 120 is kept in normal position by a spiral spring. At one end of the lever is fixed a contact F^X and at the other end a piece of soft iron, (an armature,) arranged above the magnet E. This contact might be of any suitable shape, 125 so that it can close and open the connection between F and G. This arrangement is identi- 130

tical with that described (with the same reference-letters) in Patent No. 590,398, and said patent also fully describes the arrangement and construction of the contacts in the groups 5 of electromagnets A_n B_n C_n and A_p , B_p , and C_p . These contacts are made by little trolleys running on small rails which are fixed to a ring. The wires 15 and 16 connect P and Q with the wires of contact c^9 . The current 10 from P Q passes through contact c^9 to the movable electromagnet m' m^2 , and accordingly the latter will turn to the right or left, depending upon the polarity of the impulse from P and Q .

It is immaterial whether the electromagnet 15 m' m^2 moves to the right or left, and in either case the contact c^9 will be opened or broken. When the electromagnet m' m^2 moves to the left, the contact at c^2 will be closed, and under the influence of the source of electricity 20 H and the connection through the wires 17 and 18 the said electromagnet m' m^2 will be kept in the position. If, however, the said electromagnet moves to the right, the contact at c' will be closed, and said electromagnet, 25 through this contact, is kept in position.

If the impulse from P is negative, the electromagnet m' m^2 in A_n will turn to the right, the contact at c^9 will be opened, and the contacts at c' and c^3 closed. If a second impulse 30 from P is also negative, the same result will be obtained in the electromagnet in B_n , for the reason that the current from P will now pass through the closed contact c^3 of A_n to c^9 of B_n and from there to the electromagnet 35 m' m^2 of B_n . (The magnet in B_n will turn to the right.)

By every successive negative impulse from P the successive electromagnet m' m^2 of the respective groups A_n B_n C_n will turn to the 40 right and are kept in that position.

If, on the contrary, after one negative impulse from P , which has turned the electromagnet m' m^2 of A_n to the right, a positive impulse follows, (the current reaching the 45 electromagnet m' m^2 of B_n through the contacts c^3 of A_n and c^9 of B_n .) the electromagnet m' m^2 of B_n is turned to the left. By this movement contacts c^7 of B_n will be closed, while contact c^3 of B_n remains open. (Contact 50 c^7 of B_n is a contact of the second horizontal group of signals.) Whatever impulse from P will be the next, negative or positive, none of the following groups of magnets in A_n B_n C_n can be reached, as the contacts c^9 55 and c^3 of B_n are both opened; but the turning of the electromagnet in B_n to the left has closed also contact c^{10} in B_n , and by the closing of this contact any impulse from P can now reach the second group of magnets in A_p B_p C_p . The current from P will go through wire 60 19, wire 20, contact c^{10} in B_n , and wire 21 to connection-screw P_p and can reach from here the second group of magnets in A_p B_p C_p . In these groups the electromagnets m' m^2 can turn also to the right or left; but they will be 65 kept in position only if they turn to the left. If, for instance, after the positive impulse

from P , which turned m' m^2 in B_n to the left, another positive impulse follows, m' m^2 in A_p will also turn to the left. Contact c^4 in A_p 70 will be opened, but contact c^5 will be closed, and by the influence of the source of electricity H through the wires 22 and 23 the electromagnet m' m^2 in A_p will be kept in position. At the same time contact c^6 in A_p will be closed, giving the opportunity for the next 75 following impulse from P to go to the electromagnet m' m^2 in B_p . If this next following impulse is negative, the last-mentioned electromagnet will turn to the right. The only contact which then will be closed is at c^8 in B_p , this being the contact of the second vertical group of signals. Contact c^7 in B_n of the second group of horizontal signals being 80 already closed, it follows, by what has been explained above, that the signal S^5 at the cross-point of the second horizontal and second vertical group of signals will respond. At the same time that contact c^8 is closed the contact k^2 will be opened. These contacts 85 k' k^2 k^3 are arranged in the main wire from the source of electricity H . The current from H goes through wire 24, contact k' , wire 25, contact k^2 , wire 26, contact k^3 , and wire 27 to connection-screw w . The other pole of H is 90 connected by wire 28 to connection-screw v . From said connecting-screws w and v the wires run to the movable magnets m' m^2 to keep them in position after closing of the necessary contacts. It is evident that when one 95 of the contacts k' k^2 k^3 is opened the current from H stops and every magnet m' m^2 which was turned to the right or left will be returned to its rest position by means of its respective spiral spring k^0 . From this it follows that as 100 many impulses of one polarity (say negative ones) are sent from the transmitting-station through P and Q a like number of magnets m' m^2 in A_n B_n C_n will be turned to the right and kept there in position. The next impulse 105 of the opposite polarity (positive) will turn the next following magnet m' m^2 in A_n B_n C_n to the left and keep it there and at the same time close the contact of one group of signals, (say the horizontal ones). The following impulses of the same polarity (positive) turn an adequate number of magnets m' m^2 in A_p B_p C_p to the left and keep them in that position, 110 while the next following impulse of the first polarity again (negative) will turn the next following magnet m' m^2 in A_p B_p C_p to the right and close the contact of a cross-group 115 of signals (say the vertical ones) and cause the required signal at the cross-point of both groups of signals to respond, while thereafter 120 all the magnets turn back to their respective rest positions. Should, for instance, signal s^{13} , Fig. 6, respond, two impulses of one polarity are required and three impulses of the opposite polarity followed by one impulse of the first polarity. The maximum number of 125 impulses required for a signal in said Fig. 6 is for signal s^{25} four impulses of one polarity, five of the opposite polarity, and one of the 130

first polarity, making in all ten impulses, while in the system covered by my Patent No. 590,398 twenty-four impulses of one polarity followed by one impulse of the opposite polarity would be required for the responding of said signal s^{25} . The number of magnets necessary in the selecting device at the receiving-station is reduced in the same ratio.

- 10 At the transmitting-station are arranged a number of keys for the purpose of sending the required number of electrical impulses, and said number (of keys) corresponds with the number of signals at the receiving-station.
- 15 In Figs. 2, 3, and 4 is represented one of said keys. To the lower end of the hollow rod R are fixed two hollow cross-pieces p^6 p^7 . Slidably arranged in each hollow cross-piece are two contact-blocks a and b , connected with each other by a wire c . Said blocks a and b are also connected by rods M' and M^2 with a vertical rod R' , arranged within the hollow rod R and held in a raised position by a spiral spring t , so that when the rod R' of the key 20 is not depressed the blocks a and b do not touch the walls of the framework N T. Said framework is made of insulating material and consists of four walls, each having a metal strap or rail r' r^2 r^3 r^4 . Two of these straps 25 or rails r' and r^4 are continuous, (r^4 not being visible in Fig. 2 of the drawings,) while the other two, r^2 and r^3 , are interrupted or sectional—that is to say, are partially of metal and partially of insulating material. If the 30 rod R' of the key is pressed down, (together with the hollow rod R,) the contact-blocks a and b in p^6 and similar ones in the other cross-piece p^7 will press against the metal straps in the walls. Should these straps be in the 35 shape of rails, the contact-blocks a and b might be substituted by wheels or trolleys. By a further depressing of said rod R' and hollow rod R the cross-pieces will reach at last the bottom of the framework, and thus have 40 passed the various contacts in the four metal straps or rails. As soon as the said rod R' is released the blocks a and b disengage the said rails or straps, and by the action of the spiral spring I the key is returned to its normal position. During the return movement of the 45 key no contacts are made.

In Fig. 2, U represents a source of electricity at the transmitting-station connected by wires 42, 43, 44, and 45 with the metal straps or rails 50 r^2 and r^3 in such a manner that some of the metal parts of these interrupted rails are connected with the positive pole of U and others with the negative one. The two continuous rails r' and r^4 are respectively connected by 55 wires 40 and 41 with the connection-screws W and V. These screws are connected by wires with the connecting-screws P and Q at the receiving-station. In said Fig. 2 the negative pole of U is connected by wire 42 with the first two metal parts of rail r^2 and the positive pole, through wire 45, with the first 60 two metal parts of rail r^3 . The first two im-

pulses from U to V and W will render V positive and W negative. The next four parts of rail r^2 are connected with the positive pole 70 by wire 44 of U and those of r^3 with the negative pole by wire 43. The next four impulses accordingly render V negative and W positive. The last metal part of rail r^2 is again connected by a branch of wire 42 with the 75 negative and that of r^3 by a branch of wire 45 with the positive pole, so that this last impulse renders V positive and W negative.

From the above it can be seen that by depressing the key to its lowermost position two 80 impulses of one polarity, then four impulses of the opposite polarity, followed by one impulse of the first polarity, are sent from the transmitting to the receiving station.

All the keys at the transmitting-station are 85 of similar construction, except that each one contains a different number of contacts for the two kinds of polarities.

My present system for transmitting electrical signals, besides for other purposes, is 90 extremely well adapted for transmitting type-written messages by telegraphy.

If each of the signals S or s controls in some mechanical manner a key of the type-writing machine and a corresponding number of keys 95 is arranged at the transmitting-station, each pressing of a key at the said transmitting-station will be answered by the corresponding key of the type-writing machine at the receiving-station.

Some type-writing machines are provided with shift-keys, which in some way or another control the other keys, and in such a case and in any other case where shift-keys are used an additional arrangement to those heretofore 105 described is added and is illustrated in Fig. 7. As Bs Cs are the upper parts of groups of magnets as described in connection with Fig. 1. D is a source of electricity at the receiving-station, and Sk' , Sk^2 , and Sk^3 are signals which control, mechanically, the shift-keys above mentioned. c^{12} c^{12} are contacts attached to the magnets of As Bs Cs. It is evident that through the wires shown in Fig. 7 signal Sk' will respond on closing contact 110 c^{12} in As, while Sk^2 will respond on closing contact c^{12} in Bs, and Sk^3 on closing c^{12} in Cs. These groups of magnets are arranged in front of the groups of magnets An Bn Cn. The lower parts of the groups As Bs Cs are 115 exactly the same as the lower parts of An Bn Cn in Fig. 1 and also the connection of these parts by wires to P and Q and to V and W. The connection by wires of the groups As Bs Cs to the groups An Bn Cn will be exactly the 120 same as the connection between the groups An Bn Cn and groups Ap Bp Cp. Now it is evident that if positive impulses are sent from P to the groups As Bs Cs (negative impulses are being transmitted to An Bn Cn) the magnets in As Bs Cs will turn to the left and be 125 kept in that position in a manner as above described in connection with the other groups. If a negative impulse comes from P, a mag-

130

net in As Bs Cs will turn to the right and be kept in that position; but in this case a contact c^{12} will be closed, and one of the signals S_k will respond. Therefore if the second signal is required to respond one positive impulse from P, followed by a negative one, must be sent. The further impulses are transferred to the groups An Bn Cn. The keys at the transmitting - station under these circumstances remain of the same construction, with the exception that one or more metallic sections or contacts are added to the straps or rails r^2 and r^3 for the necessary additional polarities.

15 Supposing there is at the receiving-station a type-writing machine (or some other mechanical contrivance) provided with twenty-five keys controlled by two shift-keys, if it is desired to respond the fourteenth key (corresponding to s^{14} in Fig. 6) under the influence of the second shift-key one impulse of one polarity, (positive,) three impulses of the opposite polarity, (negative,) four of the first polarity, (positive,) followed by one impulse 20 of the second polarity (negative)—all together nine impulses—must be sent from the transmitting-station.

When in the claims I use the term "succeeding" in connection with the transmission 30 of impulses, I wish it to be understood that I use this term in its most comprehensive sense and not as meaning necessarily that a certain impulse follows a certain other impulse directly or immediately.

35 Having thus described my invention, what I claim as new, and desire to secure by Letters Patent, is—

1. The combination of two sets of devices adapted to coactively operate, means for sending electrical impulses of both polarities, and electrically-controlled means, distinct from each other and actuated by said impulses, for operating the respective devices, said means being adapted to effect a coaction of their respective devices when one is actuated by an impulse opposite in polarity to, and succeeding, the last actuating impulse of the other, substantially as described.

2. In an electrical apparatus, the combination of an electric circuit open at two points therein, means for sending electrical impulses of both polarities and electrically-controlled means, distinct from each other and actuated by said impulses, for closing the respective openings, said means being adapted to effect a coincident or contemporaneous closure of their respective circuit-openings when one is actuated by an impulse opposite in polarity to, and succeeding, the last actuating impulse of the other, substantially as described.

3. In an electrical apparatus, the combination of an electric circuit open at two points therein, means for sending electrical impulses of both polarities, and two sets of electrically-controlled devices, distinct from each other, for closing the respective openings, said devices being adapted to be actuated by the im-

pulses and said circuit-openings being adapted to be coincidentally or contemporaneously closed when a device of one set is actuated by an impulse opposite in polarity to, and succeeding, the actuating impulse of the last-actuated device in the other set, substantially as described.

4. The combination of a transmitting device comprising means for sending a predetermined number of impulses of different polarities, a circuit having a source of electricity, contacts in said circuit, two coacting series of groups of magnets operatively connected with said transmitting device and controlling said contacts, and devices in said circuit controlled by said contacts, coaction between magnets of the two series being adapted to be effected when a magnet in one series is actuated by an impulse opposite in polarity to, and succeeding, the actuating impulse of the last-actuated magnet in the other series, substantially as described.

5. The combination of a transmitting device comprising means for sending a predetermined number of impulses of different polarities, a circuit having a source of electrical energy, contacts in said circuit, two coacting series of groups of magnets operatively connected with said transmitting device, some of said magnets controlling said contacts and being adapted to coactively operate, when a magnet of one series is actuated by an impulse opposite in polarity to, and succeeding, the actuating impulse of the last-actuated magnet in the other series, other contacts, and a separate circuit including said contacts and a suitable source of electrical energy, said last-named contacts being controlled by the remaining magnets, substantially as described.

6. The combination of a transmitting device comprising means for sending an impulse or impulses of one polarity alternately with an impulse or impulses of the opposite polarity, a main line, a source of electricity, two series of groups of magnets, each group having two stationary magnets and one movable one, contacts in the main-line circuit, a separate circuit in the two series of groups of magnets, contacts in said separate circuit, a receiving device comprising a series of electromagnets arranged in horizontal and vertical groups respectively, contacts in each series of groups of magnets controlling the respective electromagnets in the horizontal and vertical groups, all contacts being controlled by the movable magnets, substantially as and for the purposes described.

7. The combination of a transmitting device comprising means for sending an impulse or impulses of one polarity alternately with an impulse or impulses of the opposite polarity, a main line, a source of electricity, two series of groups of magnets, each group having two stationary magnets and one movable one, contacts in the main-line circuit, a separate circuit in the two series of groups of magnets,

contacts in said separate circuit, a receiving device comprising a series of electromagnets arranged in horizontal and vertical groups respectively, a circuit for said receiving device, 5 contacts in each series of groups of magnets and in the last-mentioned circuit and controlling the respective electromagnets in the horizontal and vertical groups, all contacts controlled by the movable magnets, substantially as and for the purposes described.

8. The combination of a transmitting device comprising means for sending an impulse or impulses of one polarity alternately with an impulse or impulses of the opposite polarity, 15 a main line, a source of electricity, two series of groups of magnets, each group having two stationary magnets and one movable one, contacts in the main-line circuit, a separate circuit in the two series of groups of magnets, contacts in said separate circuit, a receiving device comprising a series of electromagnets arranged in horizontal and vertical groups respectively, a circuit for said receiving device, contacts in each series of groups 20 of magnets, the contacts of one series of groups of magnets being connected with one pole of the source of electricity of the receiving-device circuit and with the electromagnets in the horizontal group, and the contacts of the 25 other series of groups of magnets being connected with the electromagnets in the vertical group and with the other pole of the source of electricity of said receiving-device circuit respectively, all contacts controlled by the 30 movable magnets, substantially as and for the purposes described.

9. The combination of a transmitting device comprising means for sending an impulse or impulses of one polarity alternately with an 40 impulse or impulses of the opposite polarity, a main line, a source of electricity, two series of groups of magnets, each group having two stationary magnets and one movable one, contacts in the main-line circuit, a separate 45 circuit in the two series of groups of magnets, contacts in said separate circuit, a receiving device comprising a series of electromagnets arranged in horizontal and vertical groups respectively, contacts in each series of groups 50 of magnets controlling the respective electromagnets in the horizontal and vertical groups, and a contact-breaker for each of the electromagnets in the receiving device, substantially as and for the purposes described.

55 10. The combination of a transmitting device comprising means for sending an impulse or impulses of one polarity alternately with an impulse or impulses of the opposite polarity, a main line, a source of electricity, 60 two series of groups of magnets, contacts controlled by their respective series, a receiving device comprising a series of electromagnets arranged in horizontal and vertical groups respectively and controlled by contacts of 65 both series of magnets, and a contact-breaker for each of the electromagnets in the receiving device, substantially as and for the purposes described.

ing device, substantially as and for the purposes described.

11. The combination of a transmitting device comprising means for sending an impulse or impulses of one polarity alternately with an impulse or impulses of the opposite polarity, a main line, a source of electricity, two series of groups of magnets, each group having two stationary magnets and one movable one, contacts controlled by their respective series, a receiving device comprising a series of electromagnets arranged in horizontal and vertical groups respectively and controlled by contacts of both series of groups of 80 magnets, and a contact-breaker for each of the electromagnets in the receiving device, substantially as and for the purposes described.

12. The combination of a transmitting device comprising means for sending an impulse or impulses of one polarity alternately with an impulse or impulses of the opposite polarity, a main line, a source of electricity, two series of groups of magnets, each group having two stationary magnets and one movable one, contacts in the main-line circuit, a separate circuit in the two series of groups of magnets, contacts in said separate circuit, a receiving device comprising a series of electromagnets arranged in horizontal and vertical groups respectively, a circuit for said receiving device, contacts in each series of groups of magnets and in the last-mentioned circuit and controlling the respective electromagnets in the horizontal and vertical groups, 100 all contacts controlled by the movable magnets, and a contact-breaker for each of the electromagnets in the receiving device, substantially as and for the purposes described.

13. The combination of a transmitting device comprising means for sending an impulse or impulses of one polarity alternately with an impulse or impulses of the opposite polarity, a main line, a source of electricity, two series of groups of magnets, each group having two stationary magnets and one movable one, contacts in the main-line circuit, a separate circuit in the two series of groups of magnets, contacts in said separate circuit, a receiving device comprising a series of electromagnets arranged in horizontal and vertical groups respectively, a circuit for said receiving device, contacts in each series of groups of magnets, the contacts of one series of groups of magnets being connected with 115 one pole of the source of electricity of the receiving-device circuit and with the electromagnets in the horizontal group, and the contacts of the other series of groups of magnets being connected with the electromagnets in the vertical group and with the other pole of the source of electricity of said receiving device respectively, all contacts controlled by the movable magnets, and a contact-breaker for each of the electromagnets in the receiving device, substantially as and for the purposes described.

14. In a system of transmitting electric signals having a source of electricity, a main line, two or more series of groups of magnets, contacts controlled thereby, a receiving device controlled by the contacts, a transmitting device comprising two or more keys, each key controlling a certain number of magnets and being adapted to send impulses of both polarities, and two coacting sets of circuit-closers actuated by said magnets, coaction between magnets of the two sets being adapted to be effected when a magnet in one set is actuated by an impulse opposite in polarity to, and succeeding, the actuating impulse of the last actuated magnet in the other series, substantially as described.

15. In a system of the character described, a transmitting-key comprising a framework, a series of continuous metallic rails on said framework, a series of interrupted or sectional metallic rails also on said framework and diagrammatically opposite the said continuous rails and adapted to coöperate with the same, a hollow rod, hollow cross-pieces carried by said rod, contact-blocks slidingly arranged in the respective cross-pieces, a spiral spring controlling said cross-pieces and hollow rod, and a spring-controlled rod within the hollow rod and controlling the slidingly - arranged contact-blocks, all said parts, substantially as and for the purposes described.

16. In an electrical apparatus, the combination of two sets of devices adapted to coactively operate, means for sending electrical impulses of both polarities, two sets of electrically - controlled magnets, distinct from each other and actuated by said impulses, for operating the respective devices, said mag-

nets being adapted to effect a coaction of their respective devices when one is actuated by an impulse opposite in polarity to, and succeeding, the last actuating impulse of the other, another magnet or set of magnets electrically connected to, and disposed between, the impulse-sending means and the one of the first-named set of magnets adjacently connected to the latter, and a device or set of devices controlled by said last-named magnet or set of magnets, substantially as described.

17. In an electrical apparatus adapted to control a type-writer or other similar printing-machine having shift-keys, the combination of two sets of devices adapted to coactively operate, means for sending electrical impulses of both polarities, two sets of electrically - controlled magnets, distinct from each other and actuated by said impulses for operating the respective devices, said magnets being adapted to effect a coaction of their respective devices when one is actuated by an impulse opposite in polarity to, and succeeding, the last actuating impulse of the other, another set of magnets electrically connected to, and disposed between, the impulse-sending means and the one of the first-named set of magnets adjacently connected to the latter, and a set of shift-key-controlling devices controlled by said last-named set of magnets, substantially as described.

In testimony that I claim the foregoing I have hereunto set my hand this 14th day of May, 1898.

SIMON DE JAGER.
